INHALER

George P. Trumbour, Needham, and Harlan I. Prater, Jr., Wellesley Hills, Mass., assignors to MacGregor Instrument Company, Needham, Mass., a corporation

Application June 25, 1949, Serial No. 101,398

7 Claims. (Cl. 128—206)

1

Our present invention relates to inhalers and particularly to inhalers for use with medicaments such as powdered penicillin.

Where such medicaments are to be taken by inspiration, it is essential that the patient receive the full dosage prescribed and it is to inhalers that enable that result to be effectively attained and that, at the same time, are adapted to economical production that our invention is directed.

In accordance with our invention, we provide an inhaler comprising a body having a passage extending from its butt to its tip and being of increased cross sectional area adjacent the butt. A cap, serving as a container for the medicament, is detachably connected to the butt with its closed end spaced from the enlarged extremity of that passage and our inhaler has air intake passages in communication with the interior of the cap and disposed towards its closed end.

In practice, we provide that the flow of intake air is accelerated in the zone of the butt end of the body passage to ensure that air drawn into the cap is in the form of streams sweeping its inner surfaces to the closed end thereof with the result that all the medicament may be picked up by the inspirated air stream.

We also provide the inhaler body with a valve in control of the passage. The valve includes a valve element and first and second spaced seats therefor. The element engages the first seat under the influence of exhaled air thereby preventing moisture from that source causing the powdered medicament to agglomerate. When the patient inhales through our inhaler, the valve element is lifted from the first seat but the second seat is grooved so that should it be engaged by the valve element, the passage will remain open.

In the accompanying drawings, we have shown an illustrative embodiment of our invention from which these and other of its novel features and advantages will be readily apparent.

In the drawings:

Fig. 1 is a longitudinal section, on an enlarged scale, of an inhaler in accordance with our invention, and

Figs. 2 and 3 are sections along the lines 2—2 and 3—3, respectively, of Fig. 1.

In accordance with our invention, we provide an inhaler consisting of a body 5, preferably of tubular form, having one end rounded to provide a tip dimensioned so that it is adapted for both nasal and oral uses. A cap-like vial 6 con-

2

taining the medicament 7 is detachably connected to the butt end of the body 5. The body 5 has a passage 8 extending from end to end thereof and the inhaler has intake passageways 9 in communication with the interior of the cap 6.

In order that all the medicament 7 may be inspired through the passage 8, we dispose the intake passageways 9 so that they are remote from but directed towards the closed end of the cap 6 and form the passage 8 so that its adjacent end 10 is of greater cross sectional area than the tip end thereof. By this construction, entrant air streams over the inner surfaces of the cap 6 and sweeps the medicament therefrom and from its closed end into the stream through the passage 8, the mouth 10 of which is suitably screened as at 11.

While any type of connection between the inhaler body 5 and its cap 6 may be employed, we prefer to utilize a friction fit between them. For that reason, the mouth of the cap 6 is slightly tapered to fit securely on the correspondingly tapered butt 12 of the body 5 and be seated against the body shoulder 13. Extending the full length of the butt 12 and intersecting the shoulder 13 are a plurality of spaced grooves which, in the assembled inhaler, establish the intake passageways 9. We prefer this construction as it ensures that the streams of air drawn into the cap 6 are in contact with its inner surfaces.

While a thus constructed inhaler is very satisfactory in use and is adapted to economical production, it is desirable to have the passage 8 valve controlled to prevent air, exhaled by the patient, from entering the interior of the cap 6 for the moisture carried by that air would be picked up by the medicament with such resulting agglomeration as to destroy its utility.

In order to provide such a valve, we have shown the body 5 as including an extension member 14 having a tapered neck 15 fitting into the correspondingly tapered end of a passage chamber 16. The chamber 16 is of substantially greater cross sectional area than the adjacent portions of the passage 8 and receives the valve element 17, preferably a ball. The shoulder established by the received end of the neck 15 establishes a first seat 18 for the valve element and spaced therefrom is a second seat 19. In practice, we form the valve chamber 16 with a plurality of spaced grooves 20 which intersect the seat 19 and provide lands 21 which serve to closely confine the valve element as it travels between its seats.

By this construction, the valve element 17 is

drawn from engagement with its seat 18 as the patient inhales and even should it engage the seat 19, a free passageway for inspirated air is ensured. At all times, the valve element 17 is positively guided and immediately reengages the seat 18 if the patient exhales with the inhaler still positioned for use. In practice, however, the valve element 17 seldom engages the second seat 19 but tends to flutter against the first seat 18.

Apart from its use in the establishment of the valve, the extension member 14 has an important function in the desired operation of our inhalers. The extension member 14 is dimensioned to fit freely within the cap 6 to provide an annular air chamber 22 which is part of the air intake system. In practice, the extension member 14 is tapered as at 23 and the inner surface of the walls of the vial taper inwardly towards the closed end thereof so that the mouth 24 of the chamber 22 is of substantially reduced cross sectional area as compared with its other end. As a result, the stream of entrant air is accelerated in the zone of the screened end or mouth of the passage 8 where the inspirated air stream has not attained its full velocity thereby ensuring that the stream of entrant air is effective to sweep the entire interior of the vial 6, including its closed end.

It will be apparent from the foregoing that inhalers in accordance with our invention are well adapted for use in the accurate administration of powdered medicaments and to efficient and economical production.

What we therefore claim and desire to secure by Letters Patent is:

1. An inhaler comprising a body having a tip, a butt, and a passage effecting communication therebetween, and a cap constituting a medicament container attached to said body with its closed end spaced from the butt end of said passage and its walls spaced from the extremity of said butt and thereby to establish an air chamber having its mouth opening towards said closed end, said inhaler having inlets in communication with said air chamber and the mouth of said chamber being of restricted size so that the streams of intake air are accelerated in the zone of the butt end of said passage.

2. The inhaler of claim 1 in which one of the adjacent surfaces of the cap and butt extremity is inclined towards the other so that the air chamber tapers towards its mouth.

3. An inhaler comprising a body having a tip, a butt, and a passage effecting communication therebetween with its butt end of greater cross sectional area than its tip end, and a cap con-

stituting a medicament container attached to said body with its closed end spaced from the butt end of said passage and its walls spaced from the extremity of said butt thereby to establish an air chamber having its mouth opening towards said closed end, said inhaler having inlets in communication with said air chamber and the mouth of said chamber being of restricted size so that the streams of intake air are accelerated in the zone of the butt end of said passage.

4. An inhaler comprising a body having a tip, a butt, and a passage effecting communication therebetween with its butt end of greater cross sectional area than its tip end thereof, an intermediate portion establishing a seat, and grooves traversing said seat and at least a part of said butt end, an extension member including a neck seated in said butt end in spaced relation to said seat and having a passageway extending from end to end thereof, and a valve element confined in said butt portion by the seat established by the intermediate passage portion and by the seat established by the extremity of said neck, a cap constituting a medicament container, said cap and said body including complementary joint establishing portions connecting said cap to said body with its closed end spaced from said extension, and said extension member being dimensioned to fit freely within said cap to provide an air space, and one of said portions having passageways establishing air inlets in communication with said air space.

5. The inhaler of claim 4 in which the mouth of the passage through the extension member is funnel-shaped.

6. The inhaler of claim 4 in which the mouth of the air chamber is restricted thereby to effect an acceleration of the entrant air as it passes the open end of the passage in the extension member.

7. The inhaler of claim 4 in which the end of the extremity adjacent the butt tapers inwardly towards it and the inner surface of the cap tapers inwardly towards its closed end.
